Primary Examiner — Cynthia M. Chin(74) *Attorney, Agent, or Firm* — JEEN IP LAW, LLC(57) **CLAIM**

The ornamental design for a nail polish toy, as shown and described.

DESCRIPTION

FIG. 1 is a front, right and bottom perspective view of a nail polish toy, showing my new design;

FIG. 2 is a perspective view thereof; shown in a used condition;

FIG. 3 is a rear, right and top perspective view thereof;
FIG. 4 is a perspective view thereof; shown in an opened condition;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines shown in the drawings illustrate portions of the nail polish toy that form no part of the claimed design.
